A. S. Melundie.
ATTORNEY.

UNITED STATES PATENT OFFICE.

GEORGE W. CHRISTIANS, OF CHATTANOOGA, TENNESSEE.

HYDRAULIC JET-PUMP.

1,269,387.

Specification of Letters Patent. Patented June 11, 1918.

Application filed May 25, 1916. Serial No. 99,786.

To all whom it may concern:

Be it known that I, GEORGE W. CHRISTIANS, a citizen of the United States, residing at Chattanooga, in the county of 5 Hamilton and State of Tennessee, have invented certain new and useful Improvements in Hydraulic Jet-Pumps, of which the following is a specification.

My invention relates to a hydraulic jet 10 pump which utilizes the tendency of a stream or jet of fluid to drive or carry contiguous particles of fluid along with it.

A most important object of the present invention resides in providing a pump of 15 the foregoing class which embodies means to control or eliminate eddies adjacent the mouth of the nozzle which tend to create the back pressure which renders inefficient the most common types of hydraulic jet 20 pumps.

Another object resides in providing a nozzle having a sectional area of substantially the form of a hollow rectangular cross and wherein the suction line communicates with the channels on the exterior of 25 the nozzle body and which are formed by reason of its novel shape.

A further object resides in providing a tube which increases in cross-sectional area 30 toward the discharge end whereby the back pressure is reduced to a minimum.

Having in mind the above and other objects which will hereinafter appear I will now proceed to describe a specific embodiment by way of illustrating the principles 35 of the invention and which I have shown in the accompanying drawing wherein:

In the drawings:

Figure 1 illustrates a cross-section of a 40 concrete bay in which the pump is located,

Fig. 2 is a longitudinal control section in a vertical plane through the nozzle and a portion of the tube.

Fig. 3 is a section on the line 3—3 of 45 Fig. 2.

Fig. 4 is an end view of the nozzle and its casing; and

Fig. 5 is a section on the line 5—5 of 50 Fig. 2.

In detail:

The pump is located in the artificial bay A of concrete construction or the like and which has a head-water entrance 1 covered by the grating 2 and a tail raceway 3.

55 Entering the bay A is a suction line 4 from the waste sump or the like of a power-

house and having a riser 5 within the bay A. Connected with the riser 5 is a valve 6, which may be either of the gate or check type, in the latter case opening away from 60 the suction line 4 so as to prevent return therethrough. Connected with the valve 6 is a special T 7 which forms the casing for the nozzle, to be hereinafter described, and on the discharge side the sections 8, 9, 10, 65 11 and 12 of gradually increasing diameter in the order named from the discharge length of the tube, and the section 12 is directed upwardly so that its discharge orifice enters the tail race 3. 70

On the other side of the T 7 the head 14 of the nozzle is connected with the said T and positioned intermediate the T and a valve 15 also of either the gate or check type and in the latter case opening toward 75 the discharge. A member 16 having a flaring inlet orifice completes the tube.

The T 7 and also an intermediate section 17 are of special construction to house the nozzle and baffles to be presently described. 80

The nozzle is provided with a head and a body 18 which latter, throughout its length is hollow and of rectangular cross-shape in section and so formed that while its dimensions are substantially the same 85 in length and breadth throughout its body yet the internal passages 19, 20, 21 and 22 are tapered in area toward the head whereas the external passages 23 which communicate with the suction line are conversely 90 tapered, thus giving a comparatively large area of contact between the flow through the nozzle and the flow of the suction line. The special fitting 17 is provided on its interior with a tapered ring 24 abutting 95 the end of the nozzle as shown in Fig. 2. The fitting 17 is provided with circumferentially extending recesses 25 which have bearings 26 journaling pintles 27 upon which swing triangular baffles 28, 29, 30 100 and 31 located adjacent the channels 23 and serving to control the eddies tending to create a back pressure at the mouth of the nozzle and suction line.

The upper baffles 28, and 29, and also 105 the lower baffles 30, and 31, in the closed position shown in Fig. 2, abut the wall 32; and the lower baffles 30 and 31 differ from the baffles 28 and 29 in that the said lower baffles have air chambers 33 reinforced by 110 screws 34 and are thereby rendered buoyant. The bearings 26 are made adjustable

so that the baffles and their pivots or pintles 27 may be moved bodily toward or away from the discharge of the nozzle.

The operation is as follows:

- 5 When it is desired to draw fluid through the suction line 4 the valve 15 is opened as is also the valve in the suction line and the flow of fluid through the nozzle creates a suction and hence induces a flow in the said suction line thereby drawing a contiguous stream therefrom. When such flow is taking place the natural tendencies and influences create eddies adjacent the stream from the nozzle which would tend to diminish the 10 efficiency of the jet. Therefore the baffles 29 and 31 come into play and, by reason of their construction and location, automatically adjust themselves to the conditions under which the jet is working.
- 20 In starting the jet the normal back pressure is very low and hence the baffles open wide and permit flow through the entire area of the channels 23; however, as the back pressure increases eddies are formed which 25 tend to create a backward flow at points not adjacent the nozzle stream and the baffles adjust themselves according to the difference in pressure between the backward flowing portions of the stream and the discharge 30 and are thereby so balanced as to counteract the eddies.

While in the foregoing, I have described a specific embodiment of the present invention it is nevertheless to be understood that, 35 in practice, I may resort to such modifications as fall within the scope of the invention as defined in the appended claims.

I claim—

1. The combination in a jet pump of a T 40 of substantially the same diameter throughout its length, a nozzle arranged within said T and provided with a cross shaped passage which decreases in area toward its discharge, channels formed by the arms of the cross on the exterior of the nozzle and increasing in 45 area toward the discharge, a suction line leading into said T for conveying the material to the T, which is drawn through the T by a stream passing through said nozzle, 50 a pipe section secured to the outlet end of the T and provided with an inwardly tapered ring for directing the material passing through the nozzle and T toward the axis of the pipe section, and baffles arranged 55 in said pipe section directly in front of the channels and out of line with the nozzle passage.

2. The combination in a jet pump of a T 60 of substantially the same diameter throughout its length, a nozzle arranged within said T and provided with a cross shaped passage which decreases in area toward its discharge, channels formed by the arms of the cross on the exterior of the nozzle and increasing in 65 area toward the discharge, a suc-

tion line leading into said T for conveying the material to the T, which is drawn through the T by a stream passing through said nozzle, a pipe section secured to the outlet end of the T and provided with an inwardly tapered ring for directing the material passing through the nozzle and T toward the axis of the pipe section, and swinging baffles arranged in said pipe section directly in front of the channels and 75 out of line with the nozzle passage.

3. The combination in a jet pump of a T of substantially the same diameter throughout its length, a nozzle arranged within said T and provided with a cross shaped passage 80 which decreases in area toward its discharge, channels formed by the arms of the cross on the exterior of the nozzle and increasing in area toward the discharge, a suction line leading into said T for conveying the material to the T, which is drawn through the T by a stream passing through said nozzle, 85 and baffles arranged in front of the channels and out of line with the nozzle passage.

4. A jet pump comprising a T of substantially the same diameter throughout its length and having inlet and discharge orifices, a nozzle arranged within said T and having a cross-shaped passage of decreasing cross-sectional area toward the discharge 95 thereof, channels formed in the exterior of said nozzle by the arms of said cross and increasing in area toward the discharge end of the nozzle, a suction line leading into said T intermediate the ends of the same, a pipe 100 section secured to the outlet end of the T and provided with an inwardly tapered wall for directing the material passing through the pipe section toward the axis of the same, and automatically adjustable baffles arranged in said pipe section in front of the nozzle channels.

5. The combination in a hydraulic jet pump of a tube having inflow and outflow orifices, a suction line leading into said tube 110 intermediate the said orifices, a nozzle substantially cross-shape in section and directed toward the discharge orifice and of decreasing cross-sectional area toward the discharge thereof and the said suction line communicating with the channels formed on the exterior thereof whereby fluid passing through said nozzle induces a contiguous flow from said suction line, and buoyant baffle means to control eddies tending to create back pressure. 115

6. The combination in a hydraulic jet pump of a tube having inflow and outflow orifices, a suction line leading into said tube intermediate the said orifices, a nozzle substantially cross-shape in section and directed toward the discharge orifice and of decreasing cross-sectional area toward the discharge thereof and the said suction line communicating with the channels formed on the 120 130

exterior thereof whereby fluid passing through said nozzle induces a contiguous flow from said suction line, and automatically adjustable baffle means located at the 5 discharge ends of said channels to control eddies tending to create back pressure.

In testimony whereof I have hereunto af-

fixed my signature in the presence of two subscribing witnesses.

GEORGE W. CHRISTIANS.
